UNITED STATES PATENT OFFICE.

HENRY F. BICKEL, OF PLAINFIELD, NEW JERSEY, AND BLYTHE J. MINNIER, OF WATERTOWN, NEW YORK, ASSIGNEES TO THE NEW YORK AIR BRAKE COMPANY, A CORPORATION OF NEW YORK.

LUBRICATOR.

Application filed May 8, 1922. Serial No. 559,392.

To all whom it may concern:

Be it known that we, HENRY F. BICKEL and BLYTHE J. MINNIER, citizens of the United States, residing, respectively, at 5 Plainfield, in the county of Union and State of New Jersey, and at Watertown, in the county of Jefferson and State of New York, have invented certain new and useful Improvements in Lubricators, of which the 10 following is a specification.

This invention relates to lubricators, and particularly to lubricators used with steam engine cylinders and air pump cylinders.

The important feature of novelty is the 15 use of a jacket surrounding the oil chamber or reservoir and connected with the working space of the lubricated steam engine cylinder or air pump in such manner as to receive heat therefrom.

20 A secondary feature of novelty is the connection of a plurality of jacketed lubricators so that the various jackets receive heat from the same working space, while the individual lubricators operate to feed oil to different cylinders or working spaces. This last arrangement is peculiarly desirable with compound or multi-stage air pumps, as it permits the heated air to be taken from the highest stage, thus securing the highest temperature.

The invention has particular utility in connection with the air pumps used in railway air brake service, because such pumps are placed in exposed positions and are subject to the effects of varying atmospheric 35 temperatures.

The invention is shown and described as applied to a two-stage air pump of the type now in common use in railway air brake systems.

In the drawings:—

Fig. 1 is an elevation of a portion of the air pump and connected steam cylinders with two lubricators connected to feed oil to the respective air cylinders, and to be heated by air from the second stage or high pressure cylinder.

Fig. 2 is a plan view of the lubricator bracket with the lubricator for the second

stage cylinder in position and the lubricator 50 for the first stage cylinder removed.

Fig. 3 is a section on the line 3—3 of Fig. 2. A portion of the bracket is broken away.

Fig. 4 is a fragmentary section on the line 4—4 of Fig. 2.

The high pressure steam cylinder is shown at 1, the low pressure steam cylinder at 2, the low pressure air cylinder at 3, and the high pressure air cylinder at 4. The cylinders are connected by the usual frame structure 5. The high pressure steam piston (not shown) is connected to the low pressure air piston (not shown) by the piston rod 6. The low pressure steam piston is connected to the high pressure air piston by the piston rod 7. This is a familiar construction and obviously is subject to variation.

In Fig. 1, the lubricator for the low pressure air cylinder is indicated generally by the numeral 8, and the lubricator for the high pressure air cylinder is indicated generally by the numeral 9. These two lubricators are supported on a ported bracket 10 which is bolted to the high pressure cylinder head.

A pipe 11 provides a free communication from the working space of the low pressure air cylinder to a port 13 in the bracket 10. Similarly a pipe 12 provides an open communication from the working space of the low pressure air cylinder to a similar port 14 in the bracket 10. Leading from the port 14 is a passage 15 extending transversely of the bracket 10 and communicating with a similar port 16 extending longitudinally of the bracket 10. This port 16 serves as a manifold connection for conducting the heating air to the lubricators mounted on the bracket. It is consequently provided with two small air ports 17 and 18 which extend upward and terminate in the seats 19 and 20.

The seat 19 receives the low pressure cylinder lubricator, and the seat 20 receives the high pressure cylinder lubricator. The ports 13 and 14, previously mentioned, also terminate in the face of the seats 19 and 20. The lubricator may be of any suitable type.

For purposes of illustration, we have chosen that shown in our copending application, Serial No. 510,801, filed October 27, 1921, which has issued as Patent 1,446,412, Feb. 5, 1923.

The high pressure and the low pressure lubricators are identical except possibly for slight differences in port dimensions. Each lubricator consists of an oil reservoir 21 which is surrounded by a jacket 22. This jacket is formed with a small port 23. In the case of the high pressure lubricator shown in Fig. 3, this port communicates with the port 17 in the bracket 10. In the case of the low pressure lubricator, it communicates with a similar port 18.

The oil reservoir 21 is closed by a screw cap 24 which gives access to its interior and permits the filling of the reservoir with oil. Threaded into the body of the lubricator, and extending upward within the reservoir 21 to a point above the highest oil level therein, is a ported nipple 25. The nipple 25 is provided with an air port 26 which communicates at its lower end with the port 14 in the bracket 10, and which communicates at its upper end with the interior of the reservoir 21 by means of a lateral air port 27. The exact position of the port 27 is not material except that it is above the highest oil level in the reservoir 21.

Parallel with the port 26 is an oil port 28 which communicates with the interior of the reservoir by a relatively minute port 29 located near but slightly above the bottom of the reservoir 21. The port 28 communicates with the port 26 by a relatively minute port 30 which is opposed to the air port 27.

The operation of the oil cup may be described with reference to the high pressure lubricator shown in Fig. 3. As the piston reciprocates in the air pump, there are wide and sudden fluctuations in pressure which are communicated by the port 26 to the oil reservoir. These pressure fluctuations lead to the injection of minute quantities of oil through the port 30 into the air port 26. The oil meets the air entering through the ports 27 and is atomized and carried to the air cylinder through the pipe 12. These same surges of pressure in the pipe 12 lead to the flow of compressed air to the jackets 22, and, as this air is heated by the compression of the pump, it leads to the maintenance of suitable elevated temperatures of the oil in the reservoirs 21.

It will be noted that the jackets 22 of both lubricators are connected to the high pressure air cylinder through the pipe 12. The pipe 12 thus serves not only to heat both lubricators, but to conduct the oil from the high pressure lubricator to the high pressure cylinder. Pipe 11 merely serves to

conduct oil from the low pressure lubricator to the low pressure cylinder.

The invention is particularly applicable to any lubricator of the class in which surges of pressure fluid back and forth between the working space of the cylinder and the reservoir of the lubricator serve to transfer the oil from the reservoir to the cylinder, as there is inherently present in this type of lubricator the necessary air connection from which the supply of jacket air may be derived. The invention is, however, applicable to other types of lubricator, and we do not mean even by implication to limit our claims to the use of this particular type of lubricator, or to the particular example thereof shown in the drawings. The lubricator structure described herein is claimed in our copending application above identified, and consequently is not claimed in the present application.

While the various lubricators are provided with individual jackets, it is obvious that the various jackets are connected together by the manifold 16, and hence form in effect a single jacket structure. Indeed, except for manufacturing considerations, there is no reason why each lubricator reservoir should be formed with an individual jacket. In certain of the claims, we use the term "jacket structure" for the purpose of avoiding any such limiting implication.

What is claimed is:—

1. The combination of a plurality of cylinders having corresponding working spaces in which fluctuations of fluid pressure occur through different pressure ranges; a plurality of lubricators having oil reservoirs connected to feed oil to respective cylinders; a jacket structure surrounding said reservoirs; and a connection between the interior of said jacket structure and the working space of a cylinder having a high pressure range.

2. The combination of a plurality of cylinders having corresponding working spaces in each of which fluctuations of fluid pressure occur; a plurality of lubricators one for each cylinder, each lubricator having an oil reservoir, an oil-feeding port, a jacket surrounding said reservoir and a port leading to the jacket; a bracket for supporting and connecting said lubricators having oil-feeding ports connecting with the oil-feeding ports of the various lubricators and a manifold port leading from one oil-feeding port in the bracket and connecting with the jacket ports of all the lubricators; and connections from a working space of each cylinder to a corresponding oil-feeding port of the bracket.

3. The combination of a plurality of cylinders having corresponding working spaces in each of which fluctuations of fluid pressure occur; a plurality of lubricators, one

for each cylinder, each lubricator having an oil reservoir, a jacket surrounding said reservoir, a mounting seat and separate ports extending from said seat to said reservoir and to said jacket respectively; a bracket having seats for supporting and connecting respective lubricators and formed with oil ports each registering with the reservoir port of a corresponding lubricator, and a manifold port registering with the jacket

ports of the various lubricators; and connections from respective working spaces to the corresponding oil ports in the bracket and from one working space to the manifold port in the bracket.

15

In testimony whereof we have signed our names to this specification.

HENRY F. BICKEL.
BLYTHE J. MINNIER.
